METAL CHAIR FRAME SIDE

Charles P. Molla, Old Westbury, N.Y.

Application April 4, 1958, Serial No. 50,342

Term of patent 14 years

(Cl. D15—1)

Fig. 1 is a side view of a metal chair frame side, showing my new design; and

Fig. 2 is a front view of the frame side, as shown in Fig. 1, the broken lines being shown for illustrative purposes only.

I claim:

The ornamental design for a metal chair frame side, as shown and described.
